UNITED STATES PATENT OFFICE.

JAMES BISHOP, OF CARTHAGE, NEW YORK.

STUFF-REGULATOR FOR PAPER-MAKING MACHINES.

1,181,726.

Specification of Letters Patent.

Patented May 2, 1916.

Application filed December 31, 1915. Serial No. 69,527.

To all whom it may concern:

Be it known that I, JAMES BISHOP, a citizen of the United States of America, and a resident of Carthage, county of Jefferson, 5 State of New York, have invented certain new and useful Improvements in Stuff-Regulators for Paper-Making Machines, of which the following is a full and clear specification.

10 The object of this invention is to provide simple means for so regulating the flow of the stuff to the paper making machine that the paper will have a uniform weight and thickness and the principal feature of my 15 invention is that I utilize the density and the movement or flow of the pulp to bring about this result, as more fully hereinafter set forth.

20 In the drawings Figure 1 is a perspective view of an apparatus embodying my invention; Fig. 2 is a detail vertical sectional view showing more clearly the manner of adjusting the paddle.

25 In the drawing, 5 represents the usual large chest or tank into which the stock is delivered after it comes from the beater and 6 designates a comparatively small box or tank which the stock is delivered from said tank 5 by means of pipe line 7 and a suitable 30 pump 8. The stock enters the bottom of the box 6 at one side of a partition 9 extending from one end wall of the box for about two-thirds the length of the box. The stock enters the closed end of one of the channels 35 formed by the partition 9 and flows up over the upper edge of a dam 10 and thence around the end of the partition 9, over the upper edge of the dam 11 and thence back to the large tank 5 through a pipe line 12. 40 From the box or small tank 6, the stuff is delivered to the paper making machine in the usual manner through a regulable gate 13, the level of the stock in the box 6 being determined by the height of the partition or 45 dam 11, as is obvious.

Journalized on the upper edge of the box or tank 6 is a rock shaft 14 which carries a counter-weight 15 and a depending paddle 16, this paddle being so located on the shaft that it depends into the stream of pulp at a 50 point between the dam 10 and the forward end of the partition 9, so that flow of the pulp will tend to rock shaft 14 in opposition to the tendency of the counter-weight 15. 55 The paddle or plate 16 is fastened to the shaft by bolt and slot connections, as shown,

so as to be vertically adjustable on the shaft, whereby the depth to which the lower end of the paddle extends into the stream of pulp may be varied.

Attached to the shaft 14 is a fork 17 which embraces a depending flexible hose 18 so as to laterally swing the depending end of this hose when shaft 14 is rocked. The upper end of the hose is connected to a 60 water supply pipe 19 which is provided with a suitable valve 20. The lower end of the hose terminates just above the upper edge of a thin partition 21 in a small box 22, affixed to one side of the box 6. From one 65 of the compartments formed by the partition 21 extends a waste pipe 23 and from the other (the rear) pocket or cup extends a water pipe 24 whose other end is connected to the pulp-delivery pipe 7 at a point between the pump and the tank 5. 70

It will be observed that the flow of the pulp tends to swing the lower end of the paddle 16 toward the gate 13 in opposition to the counter-weight 15, and it will be 80 specially noted that the thicker the pulp stock is the greater will be the pressure against the plate. It will be understood that a constant stream of water is being delivered down through hose 18 into one or 85 the other or both of the compartments connected with pipes 23 and 24. The parts will be so proportioned and the depth of the paddle will be so regulated with respect to the weight of the counter-weight that when 90 the pulp thickens beyond a predetermined degree the effect of the paddle will be to swing its lower end nearer to the gate and thus swing the lower end of the water hose 95 18 backwardly so as to deliver more water into the compartment connected with pipe 24, whence it will be sucked into the delivery pipe 7 and be pumped up with the pulp into the box 6, thereby thinning the stock. As soon as the stock thins down to the desired 100 degree, the pressure against the paddle 16 will be relieved and it will swing back to normal position, in which position the hose 18 will, in most cases, be arranged to deliver its entire supply into the compartment connected with pipe 23. It will be seen that 105 at times the abnormal thickness of the pulp stock will not be sufficient to throw the pipe 18 entirely across the partition 21, so that at times the down-falling stream of water 110 will be divided by the upper edge of the partition so as to deliver part of it into one

partition and part into the other; in other words, it will be seen that when the parts are properly adjusted and proportioned, the stock will be thinned out to a degree that is necessary to produce the paper of the predetermined thickness and weight.

It will be observed that a feature of importance lies in having the paddle vertically adjustable on the rock shaft, so that it may be readily adjusted to the different kinds of work. Another feature of importance is the connecting of the diluting pipe 24 to the pulp-transfer pipe 7 at a point between the pump and the tank 5, whereby the pump will serve to thoroughly mix the water with the pulp before it reaches the regulating box.

It will be observed that my invention is not confined to the specific features of construction herein shown and described, but various changes may obviously be made without departing from the spirit of the invention as covered by the claims appended; for instance, it will be obvious that other means might be employed for utilizing the rocking of the shaft to regulate the amount of water delivered to pipe 24, as, for instance, the rock shaft might be arranged to operate a stop cock in a suitable supply pipe which, by the rotation of its plug, would govern the flow of water to the pump inlet. With this stop cock device, the waste pipe would be done away with, as is obvious.

Having thus described my invention, what I claim is:

1. In an apparatus of the class set forth, means for supplying a stream of pulp to a paper making machine, means for introducing a stream of water into the pulp on its way to the paper making machine for the purpose of thinning or diluting it, and devices controlled by variations in the density and lateral movement of the pulp to the paper machine for varying the quantity of water thus introduced, said devices embodying a laterally movable member immersed in the stream of pulp and adapted by its varying lateral movements to vary the quantity of water introduced.
2. In an apparatus of the class set forth, means for supplying a stream of pulp to a

paper making machine, means for introducing a stream of water into the pulp on its way to the paper making machine for the purpose of thinning or diluting it, and devices controlled by the density and movement of the pulp to the paper machine for varying the quantity of water thus introduced, said devices embodying a rock shaft, a paddle member attached thereto and arranged to depend into the stream of pulp, and means for causing the paddle member to normally swing against the current of pulp.

3. In an apparatus of the class set forth, means for supplying a stream of pulp to a paper making machine, means for introducing a stream of water into the pulp on its way to the paper making machine for the purpose of thinning or diluting it, and devices controlled by the density and movement of the pulp to the paper machine for varying the quantity of water thus introduced, said devices embodying a rock shaft, a paddle member attached thereto and arranged to depend into the stream of pulp, and means for causing the paddle member to normally swing against the current of pulp, said paddle member being adjustable vertically so as to vary the area of surface presented to the stream of pulp.

4. In an apparatus of the class set forth, a stuff chest, a stuff box, means for delivering the stuff from the chest to the box embodying a conduit and a pump, and means for introducing a stream of water into the conduit between the pump and the chest, so that the water will be mingled with the pulp as it is pumped into the box, and means controlled by the variations in the density and lateral flow of the pulp in the box for varying the quantity of water introduced, means being provided for delivering the stuff from the box to the paper-making machine.

In testimony whereof I hereunto affix my signature.

JAMES BISHOP.
